UNITED STATES PATENT OFFICE

2,289,361

COOLING SYSTEM FOR CENTRIFUGAL
CASTING MOLDSMaurice F. Healy, Watertown, and Harold B.
Wessenger, Medford, Mass.

Application September 12, 1941, Serial No. 410,616

9 Claims. (Cl. 22—65)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to centrifugal casting molds, and in particular to a cooling system therefor.

The heating of casting machines, both in the mold and in the bearings, is a limiting factor should continuous operation or marked increase in production be desired.

According to the invention, means are provided for drawing air from the atmosphere at each end of the machine into and through a space between the mold and the rotor, or mold-actuating device, a free path having been provided. A sheet metal manifold is constructed around the revolving rotor, and the heated air is drawn out of this space through ports in the rotor by means of an exhauster. Leakage of air from outside into the manifold is minimized by a labyrinth on the manifold edge at the rotor. The distribution of cooling air along the length of the machine is controlled by adjustable ports in the machine at its ends.

It is therefore an object of this invention to provide a cooling system of improved efficiency for centrifugal casting molds.

It is a further object of the invention to provide a novel method of air cooling for centrifugal casting molds employing the exhaust principle.

It is a further object of the invention to provide a cooling system for centrifugal casting molds combining exhaustion of cooling air and regulable air entry ports.

The specific nature of the invention as well as other objects and advantages thereof will clearly appear from a description of a preferred embodiment as shown in the accompanying drawings in which:

Figure 1 is a side view in axial section of a casting mold and rotor,

Figure 2 is a section taken on the line 2—2 of Figure 1,

Figure 3 is a section taken on the line 3—3 of Figure 2,

Figure 4 is a section taken on the line 4—4 of Figure 2, and

Figure 5 is an end view of the pouring end of the mold.

Units of the casting machine not essential to an understanding of the invention have been omitted from the drawings.

Referring to the drawings by characters of

reference, there is shown in Figure 1 a chill mold 1 received in a rotor 2 and spaced therefrom by means of ring inserts 3. The latter are bored at circumferential intervals as shown at 4 to maintain an air passage between the mold and rotor.

At each end of the mold 1, intake passages 5 are provided, and bolted in juxtaposition thereto are plates 6 having perforations 7 which may be brought into varying degrees of registration with passages 5 when plates 6 are rotated, for which purpose arcuate slots 8 are provided in the plate (see Figure 5). The plate is fixed in the desired position by tightening down on bolts 9.

A baffle 10 is provided on the mold 1 immediately under exhaust ports 11. In the form shown this comprises an annular member with sloping faces to form a V-section and may be reinforced as by radial members 12. Screws 13 serve to fix the baffle to the mold.

Surrounding the exhaust ports 11 is an annular exhaust manifold 14 of generally channel shape inwardly, which opens into the main exhaust line 15, square in section, but which may also be round, or square at the manifold, merging into round.

The manifold 14 is reinforced at its outer corners by welded angle bars 16, and is fixed to uprights 17 on the bed 18 of the machine by brackets 19. Leakage of outside air into the manifold is minimized by the provision of a labyrinth consisting of a series of annular plates 20, 21 preferably aluminum, of staggered internal diameters to provide air traps 22. The inner edges of protruding plates 21 will preferably be bevelled to enhance the blocking action of the labyrinth.

For the purpose of mounting the labyrinth, an underslung structure is provided in the form of two angle bars 23, 24 welded back to back with the upper one 23 welded to the manifold 14. The annuli forming the labyrinth are carried on bolts 25 received in nuts 26 which may be welded to the angle 24 to facilitate assembly and removal. A washer 27 may be included. The outer ends 45 of bolts 25 are carried by a plate 28 which is fixed to the manifold by means of bolts 29 and 30 threaded into a receiver bar 31 inside the manifold. A washer 32 of a thickness approximating that of the angle bar 23 is provided on upper bolt 30. Spring washers 33 should be employed on the bolts in view of the vibrations. The sturdy suspension shown will effectively resist the vibration encountered, and the strength may be increased by the provision of a strengthening rib or flange 34 on the plate 28. Cross bracing of

the manifold is afforded by tubes 35 welded by their ends to the opposite inner walls of the manifold. (See Figures 2 and 5.)

Sufficient initial clearance is provided between the rotor and the labyrinth to allow for radial expansion of the rotor, and the center of the manifold is spotted in position to coincide with the center of the exit ports 11 when the rotor has attained its full longitudinal expansion.

We claim:

1. For use with a centrifugal casting machine, an air-cooling device comprising an annular manifold of generally channel shape with a central opening of a size to exceed but approximate the diameter of the casting machine, an annular baffle on said manifold at said central opening comprising plates of alternately large and small inner diameter to form a labyrinth for inhibiting the passage of air between the manifold and the machine.

2. In combination, a centrifugal casting mold and rotor therefor surrounding said mold and spaced therefrom, ports in said rotor and an annular exhaust manifold surrounding said ports, entry ports in said rotor, and means for varying the effective size of said entry ports.

3. In the combination as in claim 2, a longitudinally serrated inner rim on said annular manifold.

4. A centrifugal casting mold rotor, exhaust ports therein and an exhaust manifold surrounding said ports, the center of said manifold being normally positioned out of line with the center of said ports an amount approximating the dis-

tance moved longitudinally by said ports by thermal expansion.

5. A centrifugal casting machine comprising a rotary mold, a rotor surrounding said mold and spaced therefrom to provide a passage for cooling air, air entry ports at the ends of said passage, air exit ports spaced on a peripheral line of said rotor, and an annular exhaust manifold surrounding said exit ports, said manifold being generally channel-shaped and having serrated inner rims.

6. A centrifugal casting machine as in claim 5, said manifold being generally channel-shaped, wherein the sides of said manifold comprise plates of alternately large and small inner diameter to form a labyrinth for inhibiting the passage of air between the manifold and the exterior of the rotor.

7. In a centrifugal casting machine as in claim 20 5, an annulus on the mold aligned with the exit ports for deflecting air thereto in the passage.

8. An air exhausting manifold comprising an annular housing of channel section, a stack of annular plates of alternately large and small inner diameter fastened to each side of said housing and forming the inner rims thereof.

9. For use with a centrifugal casting machine, an air-cooling device comprising an annular manifold having side portions and an outer peripheral portion defining a generally channel section, the inner rims of said side portions being serrated axially of the manifold to a depth less than the depth of said side portions.

MAURICE F. HEALY.
